(57) **CLAIM**

The ornamental design for a clip for a door assembly of an animal enclosure, as shown and described.

DESCRIPTION

FIG. 1 is a perspective view of a clip for a door assembly of an animal enclosure shown in environmental use according to the present design;

FIG. 2 is a second perspective view thereof;

FIG. 3 is a front view thereof;

FIG. 4 is a left side view thereof;

FIG. 5 is a right side view thereof;

FIG. 6 is a top view thereof;

FIG. 7 is a bottom view thereof; and,

FIG. 8 is a rear view thereof.

The broken lines shown represent unclaimed subject matter and form no part of the claimed design.

1 Claim, 3 Drawing Sheets
